UNITED STATES PATENT OFFICE.

WILLIAM TRAPNELL, OF WESTON, WEST VIRGINIA.

POWER HAMMER.

Application filed August 19, 1925. Serial No. 51,193.

My invention relates to improvements in power hammers of the type capable of use for tamping, drilling, cutting, riveting, and the like.

5 An important object of my invention is the provision of a device of the above-mentioned character which will be a power unit, complete in itself and therefore readily portable.

10 Another object of my invention is to provide an improved arrangement of the fuel tank and means for feeding said fuel.

15 Still another object of my invention is the provision of a device of this character which is a complete compact unit which is symmetrical and easily handled, and which may be used in any position.

20 A further object of my invention is the provision, in a device of this character, of improved means for transmitting motion to the hammer element.

25 Another object of my invention is to provide a device of this character which will be inexpensive to manufacture, strong and durable.

Other objects and advantages of my invention will be apparent during the course of the following description.

30 In the drawings which form a part of this specification and wherein like characters of reference denote like or corresponding parts throughout the same,

35 Figure 1 is a central vertical sectional view through my improved tool, parts being in elevation,

Figure 2 is a central vertical section taken at right angles to Figure 1,

Figure 3 is a top plan view of my device,

Figure 4 is a bottom plan view,

40 Figure 5 is a horizontal section taken above the cylinder on the line 5—5 of Fig. 1,

Figure 6 is a detail perspective view of the parts utilized for transmitting motion from the piston to the hammer,

45 Figure 7 is a sectional view of the fuel pressure valve,

Figure 8 is a front elevation of the fan element,

50 Figure 9 is a sectional view of the same parts being in elevation, and,

Figure 10 is a detail elevation of the upper portion of a tool adapted for use in the hammer.

55 In the drawings, wherein for the purpose of illustration is shown a preferred embodiment of my invention, the numeral 11 design-

nates the crank case casting having an upper horizontal flange 12 and a lower horizontal flange 13 preferably cast integrally therewith. A cylinder 14 is secured to the flange 12 and has a depending skirt portion 15 extending down into the bore of the crank case.

Two concentric and preferably cylindrical walls 16 have the space between them closed at their lower end by the flange 12 of the crank case to which they are secured, and at the top by a cover plate 17 which is provided with a stopper 18. The walls 16 form a fuel tank surrounding the cylinder 14 but spaced therefrom. The space within the inner wall is closed at the top by a plate 19 provided with a series of openings 20 which are adapted to be covered and uncovered by a shutter plate 21 having corresponding openings and pivoted at its center by the bolt 22 which is provided at its outer end with a knob for turning the plate 21 to regulate the flow of air to the space between the tank and the cylinder. A suitable handle 23 is secured to the plate 20 by means of ears 24 preferably formed integrally with the plate 20.

The crank shank consists of a pair of stubs 25 and 25' journalled in bearings 26 which are arranged in the walls of the crank case. Eccentrics 27 are arranged at the inner ends of the stubs and are provided with a crank pin 28 to which the connecting rod 29 is pivotally secured at one end, and secured to the piston 30 at its other end. The outer ends of the stubs 25 and 25' are tapered. The stubs, eccentrics and crank pin are preferably formed integrally. On the tapered end of the stub 25 a fan 31 is arranged. This fan turns with the stub due to the key 32, and is arranged within the casing 33 formed on the crank case casting. The fan is comprised of a circular plate 34 having a hub 35 at its center and a rim 36 to which are secured radially extending blades 37 which may or may not be provided with a second rim 38. A drum 39 is secured to the outer side of the fan disk 34 and has a flange 40. In starting the motor, a rope or the like may be passed around the drum and pulled to rotate the shaft and so turn over the motor. The fan draws air through the openings 20 around the cylinder and cooling fins, through the channel 41 and out through the 110 openings 42 in the fan casing.

On the tapered end of the stub 25' is ar-

ranged a magneto 43 which turns with the shaft and serves to balance the tool by offsetting the effect of the rotation of the fan on the end of the shaft 25. This magneto 5 may be of any conventional construction as for instance the "Eisemann" magneto. A conductor 44 leads from the magneto to the spark plug 45 at the top of the cylinder.

Straps 46 surround the eccentrics 27 and 10 have their ends bent downwardly and arranged in spaced relation. Blocks 47 are arranged between the ends of the straps and are secured in place by bolts 48. These 15 blocks are provided with openings 49 for the reception of a pin 50 which passes through the bored end of a rod 51 and pivotally secures said rod to said blocks. The rod 20 51 passes through a bearing 52 in the lower flange of the crank case casting and extends into the bore of a tubular casting 53 which is rigidly secured to the lower flange 13 by means of an upper flange 54 which is also connected to a lower flange 55 by means of webs 56 which serve to strengthen the tube 25 casting. A bushing 57 extends for the greater length of the tube and slidably receives a hammer member 58 which has its upper end provided with an elongated recess 59 closed by a cap 60 which in turn has a central bore for the reception of the reduced end of the rod 51 which is provided at its 30 end below the cap, with an enlarged head portion 61 which is shown as screwthreadedly secured to the end of the rod. A coil 35 spring 62 is arranged within the recess and presses against the enlarged head 61 of the rod 51.

Arranged within the lower end of the bore 40 of the tube 53 is the tool holder 63 held in place by means of the cap 64 secured to the lower flange 55. The tube is provided at its lower end with a second bore 65, of larger diameter than the main bore and concentric therewith, the bores being separated 45 by the sleeve portion 66. The upper end of the tool holder is reduced to fit within the inner bore of the tube, and a coil spring 67 is arranged within the outer bore and bears against the shoulder formed by the reduced portion of the tool holder. The tools to be used with the hammer have their top portions provided with bayonet slots 68 within which set screws 69 carried by the tool holder, fit. The tool is placed in the holder and when twisted, the screws 69 will go into the end of the slots 68 and will hold the tool against displacement.

When the piston is caused to reciprocate, 50 a rotary motion is given to the eccentrics 27 which causes the rod 51 to reciprocate vertically, due to the straps 46. This motion is transmitted to the hammer through the spring 62 thereby insuring that the connecting rod will pass the bottom center. The 55 spring also absorbs the shocks and prevents

unnecessary wear on the machine. It will be seen that the hammer will be caused to reciprocate within a distance determined by the throw of the eccentrics. In the position shown in Figure 2, the hammer is free to 70 move without coming into contact with the tool holder. When it is desired to actuate the tool, pressure is put upon the machine until the tool holder is forced up, against the tension of the spring 67, into the path of 75 the hammer. The strength of the blow is determined by the pressure put upon the tool. This may be varied however by changing the spring 67. The upper spring 62 also serves to cushion the blows, and this spring 80 may be changed for greater or lesser cushioning effect.

The fuel is fed through the pipe 70 to a mixing valve 71 which is illustrated as a conventional "Lunkenheimer" valve. The 85 supply may be cut off by the valve 72 and the speed can be controlled by the throttle valve 73. The vaporized fuel is fed into the crank case where it is compressed and fed into the cylinder through the inlet port 74. 90 In order to insure proper feeding of the fuel at all times and in all positions of the machine, it is desirable to provide a pressure feed. To accomplish this, I provide a pipe 75 which connects the top of the fuel tank 95 with the crank case. A valve casing 76 is arranged adjacent the crank case in the pipe line 75 and is provided with a valve 77 held in place by a spring 78. During the compression stroke, a certain amount of compressed vapor will enter the valve 77 against the tension of the spring 78 and will be led to the fuel tank where it will press on the surface of the fuel and insure proper feeding in all positions of the tool. A second 105 valve 79 is arranged in the valve 77 and closes a port 80 connecting the pipe 75 with the crank case, through the valve 77. This valve 79 is held in place by a spring 81. When the pressure in the fuel tank becomes 110 too great it will discharge into the crank case, through the valve 79.

The charge is ignited by the plug 45 and is exhausted through the port 82. A cover casting 83 forms an expansion chamber adjacent the crank case and the gases escape through the openings 84 at low velocity. This arrangement of the expansion chamber serves to heat the walls of the crank case and raise the temperature of the combustible vapors therein, thereby increasing the efficiency of the machine.

A similar cover casting 85 covers the mixing valve and inlet side of the crank case, and is provided with integral ears 86 to 125 which a handle 87 is pivotally secured. Similar ears are formed on the casting 83 and serve to strengthen the casting and as a support for a tripod or the like.

In operation, the plate 21 will be regu- 130

lated according to the temperature etc. and the circulation of air around the cylinder, due to the action of the fan, will prevent undue heating of the fuel in the tank by conduction but the fuel will be heated to a certain extent by radiation, but not dangerously. This heating will raise the volatility of the fuel especially advantageous in cold weather. The amount of air drawn through the space between the cylinder and fuel tank may be regulated or cut off altogether by means of the shutter 21.

The arrangement of the fuel tank, fan, magneto, etc. is such as to produce maximum compactness and symmetry, and adds to the efficiency of the machine. The machine is complete in itself and may be used anywhere, and the entire construction is of the utmost simplicity.

20 While I have shown and described the preferred embodiment of my invention, it is to be understood that various changes in the size, shape, and arrangement of parts may be resorted to without departing from the spirit of my invention or the scope of the subjoined claims.

Having described my invention, what I claim as new and desire to protect by Letters Patent is:

30 1. A power hammer comprising a piston and cylinder for operating said hammer, and a fuel tank arranged concentrically about said cylinder and spaced therefrom to provide an air space about the cylinder.

35 2. A portable power hammer comprising a piston and cylinder, a fuel tank arranged concentrically about said cylinder and spaced therefrom, and a fan operated by said piston and adapted to cause a circulation of air between said cylinder and said fuel tank.

40 3. A portable power hammer comprising a piston and cylinder, a fuel tank arranged concentrically about said cylinder and spaced therefrom, a crank shaft connected to said piston, a fan on said crank shaft and adapted to cause a circulation of air in the space between said cylinder and said fuel tank, and means for regulating the amount of air circulation.

45 5. A portable power hammer comprising a piston, cylinder and crank case, a pair of tub shafts journaled in the walls of said crank case, eccentrics mounted upon the inner ends of said shafts the piston being operatively connected to the eccentrics, straps surrounding said eccentrics, a push rod pivotally secured to said straps and adapted to be reciprocated thereby, and a hammer element actuated by said push rod.

60 6. A portable power hammer comprising a piston, cylinder and crank case, a fuel tank concentrically arranged about said cylinder and spaced therefrom, a crank shaft, a fan arranged on one end of said crank shaft and adapted to cause a circulation of air in the

space between the cylinder and tank, a magneto mounted on the other end of said crank shaft and serving to preserve the balance of the tool, and a hammer element actuated by said crank shaft.

6. A portable power hammer comprising a piston, cylinder and crank case, a fuel tank concentrically arranged about said cylinder and spaced therefrom, a crank shaft journaled in the walls of the crank case, a fan arranged upon one end of the crank shaft and adapted to circulate air in the space between the cylinder and fuel tank, a magneto mounted on the other end of the crank shaft, an expansion chamber arranged adjacent the crank case and adapted to heat the walls thereof, a push rod operatively connected to the crank shaft, and a hammer element resiliently connected to the push rod.

7. A portable power hammer comprising a piston, cylinder and crank case, a fuel tank concentrically arranged about said cylinder and spaced therefrom, a pair of stub shafts journaled in the walls of the crank case, eccentrics mounted on the inner ends of the shafts, a connecting rod operatively connecting said piston and eccentrics, a fan arranged on the end of one of the stubs and adapted to circulate air in the space between the cylinder and fuel tank, a magneto mounted on the end of the other stub shaft, an expansion chamber arranged adjacent the crank case and adapted to heat the walls thereof, a tubular section secured to the crank case, a hammer element therein having an elongated recess in one end, straps surrounding the eccentrics, a push rod pivotally secured to the straps and having an enlarged end arranged in the recess in the hammer, a spring in said recess and bearing against the enlarged end of the push rod, a tool holder arranged in the lower end of the tubular section, and a spring normally holding said tool holder out of engagement with the hammer.

8. A portable power hammer comprising a crank case section having flanges at each end, a cylinder mounted upon the upper flange, a piston in said cylinder, a fuel tank mounted on said upper flange and concentrically arranged about said cylinder in spaced relation therewith, a crank shaft journaled in the walls of the crank case, a fan casing formed on said crank case and in communication with the space between said cylinder and fuel tank, a fan arranged on one end of the crank shaft and within the fan casing, said fan being adapted to circulate air in the space between the cylinder and the fuel tank, a magneto arranged on the other end of the crank shaft and serving to preserve the balance of the tool and means operatively connecting the piston and crank shaft.

I testify whereof I affix my signature.
WILLIAM TRAPNELL.
